Primary Examiner — David Muller**CLAIM**

The ornamental design for a humidity control device, as shown and described.

DESCRIPTION

The present application is related to U.S. patent application Ser. No. 14/244,589, filed on Apr. 3, 2014, entitled "Segmented Portable Humidity Control Device For An Enclosed Volume Storage Device."

FIG. 1 is a front perspective view of my new design for a humidity control device, featuring the top, front and left sides thereof;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken line showing of parts of the drawings is included for the purpose of illustrating use and environment and forms no part of the claimed design.
